UNITED STATES PATENT OFFICE.

EMANUEL PISKO, OF NEW YORK, N. Y.

MACHINE FOR BRANDING CIGARS.

SPECIFICATION forming part of Letters Patent No. 544,519, dated August 13, 1895.

Application filed June 14, 1895. Serial No. 552,833. (No model.)

To all whom it may concern:

Be it known that I, EMANUEL PISKO, a citizen of the United States, residing in the city, county, and State of New York, have invented 5 certain new and useful Improvements in Machines for Branding Cigars, of which the following is a specification.

This invention has reference to an improved machine for branding cigars with the name 10 of the manufacturer, trade-mark, or other characters denoting origin in such a manner that the branding is accomplished in a very uniform and effective manner without injury to the wrapper and with consequent small 15 waste of cigars.

In branding cigars it is absolutely necessary that the brand be produced in a clear and legible manner, and that the cigars be not injured during the branding operation. 20 This is accomplished by my improved branding-machine, in which a number of cigars are branded at the same time by a simple reciprocating motion of the mold containing the cigars, which has the advantage that a machine of comparatively simple construction 25 is obtained, which can be easily operated and which is not liable to get out of order. For this purpose my invention consists of a machine for branding cigars which comprises a bed-plate *a*, movable plates on which the mold 30 containing the cigars is placed, means for adjusting the position of the mold, means for imparting vertical reciprocating motion to said platen, a series of branding-dies supported in spring-cushioned holders, means for 35 adjusting said holders in their guide-casings, and means for heating the branding-dies, as will be fully described hereinafter and finally pointed out in the claims.

40 In the accompanying drawings, Figure 1 represents a front elevation of my improved machine for branding cigars. Fig. 2 is a plan of Fig. 1. Fig. 3 is an end elevation of the machine. Fig. 4 is a rear elevation. Fig. 5 is a vertical transverse section on line 5 5, Fig. 2, drawn on a larger scale. Fig. 6 is an enlarged vertical transverse section on line 6 6, Fig. 2; and Figs. 7 and 8 are vertical longitudinal sections both on line 7 7, Fig. 2, showing my improved branding-machine respect-

ively before branding and while the branding action takes place.

Similar letters of reference indicate corresponding parts.

Referring to the drawings, A represents the 55 bed-plate of my improved machine for branding cigars.

B is a vertically-reciprocating platen which is provided with bottom sockets *b*, which receive vertical guide-pins *a* of the bed-plate A, 60 on which the platen is guided. The middle portion of the platen is made hollow, so as to reduce the weight of the same. The platen B is covered by a top plate B' of wrought iron or steel, on which the mold M, containing the 65 cigars to be branded, is placed.

The bed-plate A is provided with an upwardly-extending rear wall A', which is preferably cast in one piece with the bed-plate, and which is provided with openings for the 70 passage of two adjustable gage-screws *m*, against the ends of which the mold M is placed. The mold M contains a certain number of cigars—say ten—there being as many branding dies D as there are cigars in the mold, so 75 that all the cigars can be branded at the same time.

The branding-dies D are made of dovetail shape and are inserted into dovetailed sockets of holders D', which are guided in a horizontal plate D², supported above the mold, said plate being cast integral with the downwardly-extending rear wall D³, which is provided with recesses *d*, through which the gage-screws *m* of the mold are passed. The rear 80 wall D³ is further provided with slots *d*³, through which clamping-screws *d*⁴ are passed, by which the rear wall D³ is connected with the rear wall A' of the bed-plate A, as shown in Figs. 3 and 4. To the upwardly-extending 90 rear plate D³ is attached a horizontal top plate D⁴, which is parallel with horizontal plate D² and provided with holes for the shanks of screw-studs *e*, which are attached at their lower ends into the upper ends of the 95 die-holders D' and provided above the horizontal plate D⁴ with nuts and jam-nuts *e*¹ *e*². Each of the die-holders D' is provided immediately between the screw-studs *e* with a socket *f*, in which is arranged a cushioning- 100

spring f' , said cushioning-spring imparting a certain up-and-down play to the branding-die D , so that the dies of all the holders yield sufficiently in case cigars are of unequal thicknesses, the cushioning of the dies also preventing too great pressure on the cigars, which would be liable to crack the wrappers and thereby damage the cigars. The openings for the dies D in the horizontal lower plate D^2 and the openings for the screw-studs e in the upper plate D^4 serve to hold the die-holders firmly in position and to guide the same vertically when they have to give slightly, according to the thickness of the cigars. The cushioning of the die-holders is an important feature of my improved branding-machines, as thereby all waste, which arises in branding-machines heretofore in use and is caused by the exertion of too great a pressure on the cigars while branding the same, is prevented. The branding-dies D are heated by means of gas-jets g , which branch in downward direction from a gas-pipe G toward the rear ends of longitudinal cavities d^o , that are formed in the holders D' above the branding-dies D . The gas-pipe G extends longitudinally through the upper part of the branding-machine, said pipe being supported by suitable keepers g^o on the rear wall D^3 . The rear wall D^3 is provided below the gas-supply pipe G , and also the top plate D^4 above the same, with air-supply openings $g' g^2$, respectively, by which the air required for combustion is supplied, the products of combustion being discharged at the front end of the longitudinal cavities d^o in the die-holders D' . The gas-pipe G is provided with a gas-cock G' for turning on the gas, and is connected by a hose with a gas-burner or any other suitable supply of gas.

Instead of moving the branding-dies toward the cigars, as is the case in the branding-machines heretofore in use, the cigars are raised toward and in contact with the branding-dies by imparting a vertical reciprocating motion to the platen B , which is accomplished by means of wedges W , which are guided in suitable ways h at the ends of the bed-plate A , said wedges engaging inclined faces B^3 at the ends of the lower corners of the platen, which are further provided with projections B^3 at their lower ends, which form stops for the upward motion of the platen. The wedges B are moved simultaneously toward or away from each other by means of angular arms r , that are pivoted to the centers of the wedges W and to the head of a T-shaped lever L , that is fulcrumed at L' to an outwardly-projecting extension A^2 of the bed-plate intermediately between the pivot of the angular arms r . The lever L is formed into a suitable handle at its outer end and is preferably located at the rear part of the machine, so that the forward motion of the lever will move the wedges inwardly—that is to say, toward each other—while the outward motion of the lever will move the wedges away from each other and

lower the mold-carrying platen B . When the platen is in raised position the cigars are pressed against the cushioned heated dies and receive thereby at the same time the impression from the same. In case of any inequality in the thickness of cigars the spring-cushioned dies "give" sufficiently so as to produce the branding without injuring the wrapper of the cigar and causing waste. As soon as the cigars have been in contact with the branding-dies for the required length of time for producing the proper branding of the same, the operating-lever is moved back again, so that the wedges are moved in outward direction and the platen with the cigars on the same is returned by gravity into its lowered position, as shown in Fig. 7. As all the motions produced in the machine are rectilinear the steady and reliable motion of the platen is obtained, so that the parts are not liable to get shaky or out of order. A number of cigars are branded at the same time by the simultaneous action of the branding-dies, so that the branding of cigars which are arranged in suitable molds is accomplished in a quick and reliable manner, all the brands being produced in clear and legible characters.

Having thus described my invention, I claim as new and desire to secure by Letters Patent—

1. In a machine for branding cigars, the combination of a vertically - reciprocating platen for the cigar mold, means for reciprocating the platen, a series of spring-cushioned dies arranged in a series parallel with the platen, and means for heating the dies, substantially as set forth.

2. In a machine for branding cigars, the combination of a bed-plate, a vertically-guided platen on the bed-plate for holding the mold, means for reciprocating said platen, branding-dies above the platen, vertically-guided and spring-actuated holders for supporting said branding-dies, and means for heating the branding-dies, substantially as set forth.

3. In a machine for branding cigars, the combination of a bed-plate, a vertically-reciprocating platen supported on said bed-plate, wedges guided in ways of said bed-plate and adapted to engage the correspondingly inclined lower ends of the platen, means for operating said wedge-blocks, and a series of vertically-guided and spring-cushioned branding-dies located above the mold placed on said platen, substantially as set forth.

4. In a machine for branding cigars, the combination of a horizontal guide-plate, die-holders guided in openings of said guide-plate, branding-dies secured to the lower ends of said holders, said holders being provided with longitudinal channels, and means for heating said branding-dies, with means for supporting a mold below the dies, substantially as set forth.

5. In a machine for branding cigars, the combination of a vertically - reciprocating

platen, a mold for containing cigars to be branded, supported on said platen, gage-screws for the mold, vertically-guided and spring-actuated branding-dies located vertically above the mold, means for heating said dies, and means for supplying the air to the heating-devices, substantially as set forth.

In testimony that I claim the foregoing as my invention I have signed my name in presence of two subscribing witnesses.

EMANUEL PISKO.
